UNITED STATES PATENT OFFICE

160,018

INK CONTAINER OR SIMILAR ARTICLE

Frances Richman, New York, N. Y.

Application July 24, 1948, Serial No. 147,747

Term of patent 14 years

(Cl. D74—8)

To all whom it may concern:

Be it known that I, Frances Richman, a citizen of the United States of America, and resident of New York, in the county and State of New York, have invented a new, original, and ornamental Design for an Ink Container or Similar Article, of which the following is a specification, reference being had to the accompanying drawing, forming part thereof.

In the drawing:

Fig. 1 is a top plan view of an ink container or similar article, showing my new design; and

Fig. 2 is a perspective view thereof, the sides not shown being substantially the same as those shown.

The dominant features of my design reside in those portions shown in full lines.

I claim:

The ornamental design for an ink container or similar article, as shown and described.

FRANCES RICHMAN.
